CHARLES A. FORWARD, OF SANTA BARBARA, AND JAMES M. GARRISON, OF GOLETA, CALIFORNIA

DEVICE FOR OPERATING CASEMENTS, TRANSOMS, AND THE LIKE

Application filed September 24, 1924. Serial No. 739,483.

This invention relates to devices for operating casements, transoms and the like, and has for an object the provision of a device which will ensure a proper closing of casements and the like and at the same time an even closing thereof. It often happens in the case of operators for transoms or casements that a portion thereof will not close evenly with a second portion thereof, as for instance 5 in casements, the top portion of the window sash will not close evenly with the bottom portion, with the result that there is a slight warp, and the present device overcomes this by suitable adjusting means.

15 A further object is the provision of operating mechanism of the above character which is easy to manufacture, novel as to structure, slightly in appearance and compact in construction, easy to manipulate and readily adjustable.

With the above and other objects in view, the invention consists in the novel and useful provision, formation, construction, association and relative arrangement of parts, members and features, all as shown in certain embodiments in the accompanying drawings, described generally and finally pointed out in 25 claim.

In the drawings:

30 Figure 1 is an elevation of the casement incorporating the invention;

Figure 2 is a fragmentary elevation on an enlarged scale showing the operating means for the casement or transom or the like;

35 Figure 3 is a fragmentary transverse sectional view on an enlarged scale and showing certain features of the operating mechanism;

Figures 4 and 5 are plan and sectional 40 views, respectively, of certain features of the operating mechanism;

Figures 6 and 7 are fragmentary cross sectional views on an enlarged scale of the adjusting means;

45 Figure 8 is a fragmentary cross sectional view on an enlarged scale and showing the method by which the operating means may be concealed in the sill; and,

50 Figure 9 is a modified form of structure from the showing of a portion of Figure 3.

Corresponding parts in all the figures are designated by the same reference characters.

Referring with particularity to the drawings, we have shown at A a pair of casement windows *a*, and which casement window in 55 each instance includes a sash member 1 enclosed within a frame 2, which frame has associated therewith the usual sill 3. The casement sashes are hinged to the frame as shown at *A*². A frame or division member 4 divides 60 the pair of casements *a*. The device for operating the casement or transom or the like, or in fact, the operating mechanism for the swinging closure is designated as an entirety 65 by B, and the same primarily includes an operating shaft *b*, a lever *c*, adjustment means *d* associated with the shaft *b* and the lever *c*, a member *e* associated with the sash and with the lever *c*, and an operating means *f* for the shaft *b*,—all of which elements are 70 used in practicing one embodiment of the invention.

The operating means for the shaft *b* is detailed in Figs. 4 and 5 and the same includes a two-part casing 5, one part as 6 being formed to confine a gear 7 and worm 8, the teeth of which worm and gear intermesh as shown at 9. The shaft of the worm is given a squared opening as shown at 10 so that the end of a handle 11 may fit within such squared opening for the purpose of turning 80 the worm. The hub of the gear 7 is given a square opening, as shown at 12, and such hub as shown in Fig. 5 is normally flush with the top and bottom surface members of such two-part casing. The casing is formed with extensions as shown at 13 and 14 which are bored so that the same may be readily secured 85 by suitable means such as shown at 15 to the sill as shown in Fig. 1 at 16 and 17. The shaft *b* is adapted to be received within the squared opening 12 in the hub of the gear 7 and the shaft extends upwardly to where it is confined by a keeper 18 attached to the top frame member. It is thus evident as far as 90 the description has proceeded, that a rotation by the handle member 11 of the worm 8 will produce rotation of the gear 7 and likewise rotation of the shaft *b*. Each member *d*, of which there may be more than one, has associated therewith a lever *c*, and such means *d* 95

100

includes a block formed with a bifurcated portion, the furcations of which are designated as 20 and 21, and such furcations are slightly spaced apart at the zone marked 22 and are likewise formed with angularly cut away or recessed portions 23 and 24. Such block is formed with a screw-threaded transverse bore 25. An extension 26 is likewise formed on the block and such extension is adapted to be connected with the lever *c*. Said block is likewise formed with a transverse bore extending through the two furcations as shown at 27 and 28 and a bolt member 29 is passed through such bore in the furcations with a nut carried by such bolt whereby the furcations can be drawn together. Adapted to have screw-threaded engagement with the screw threads of the screw-threaded bore 25 is a member 30, which member is formed at 31 with an annular groove, and it is to be noted that the said member 30 projects in part within the recessed portions 23 and 24 of the furcations. Reference to Figure 2 shows that any number of such adjustment means *d* and levers *c* may be used, and Fig. 1 shows a casement using three of such members, all of them identical in formation. In each instance the adjustment means *d* is associated with the shaft *b*, and Figs. 6 and 7 show that the shaft *b* is received within the recesses 23 and 24 and that such shaft is smaller than the cross sectional area included between the walls surrounding the recesses 23 and 24. The member 30 is really a screw provided with a central annular groove and such member can be adjusted inwardly or outwardly of the screw-threaded bore 25 by suitable means such as a screw-driver, the screw being provided with grooves 32 and 33 for this purpose, and when the shaft is within the recessed portions 23 and 24, as shown in Figs. 6 and 7, it will be seen that two side portions of such shaft are received within the groove 31 and that adjustment of the member 30 inwardly or outwardly, in accordance with such figures will wedge the shaft against the block in different positions, thus causing a different angularity to be assumed by the block with relation to such shaft. Thus, in the position shown in Fig. 6 the sides of the block *d* are approximately at right angles to a diagonal of such square shaft, while in Fig. 7 movement of the member 30 has changed such right angled position. The lever *c* includes a channel shaped member, the legs 40 and 41 of which are formed with spaced flanges 42 and 43 respectively. Adapted to be received between the base portion 44 of such lever *c*, and the legs and flanges of such lever *c*, is a friction member 45, which member may include a leaf spring 46 curvally bent as shown at 47, 48 and 49 so that the same may frictionally engage the inner surfaces of the legs 40 and 41. The said leaf spring is carried in a suitable casing 50 which is provided with cut-

away portions to allow the spring portions 47, 48 and 49 to bear against the legs of the member *c*. The casing 50 in turn is fastened by means of a pin 60 to a member *e* which is adapted to be secured to the casement sash. In this connection said member *e* has a part 61 which may be secured by screws or the like to the casement sash and a projecting part as 62 with said pin 60 secured to such projecting part. 70

In the showing of Figure 1 each casement *a* has secured to the sash portions thereof three of the members *e*; that is to say, top and bottom members and intermediate member, and that there are three adjusting means *d* carrying levers *c* for association with such members *e*. The operating means *f* is secured to the sill as shown at 16 and 17. Upon inserting the lever 11 within the squared opening of the worm shaft in the members *f*, 80 rotation will be produced in the operating shaft *b* which will produce a simultaneous rotation of the levers *c* to open or close the casements. If it should happen that the top of the casement did not close properly, but left a slightly open space at the top thereof, while the bottom closed within the sill, the adjustment of the member 30 inwardly of the showing of Figure 6 would move the lever *c* inwardly so that the top would be properly closed. Such movement would be just the contrary of the movement shown for the member 30 in Figure 7. When the casement or transom has been properly adjusted it will at all times open or close properly without further attention, unless accident occur to the same. Furthermore, when any swinging closure has been opened or closed or slightly opened, it is impossible to further open or close such swinging closure, due to the formation of the member *f*, the general principle of a worm and gear being well understood, and as the showing reveals the gear is mounted in connection with the shaft so any attempted turning of the shaft would produce a locking against the worm without any rotation. 90

The adjustment feature of this device is of great importance, as any swinging closure can be adjusted so that it will at all times 100 close properly.

In Figure 8 the device *f* has been placed beneath the sill so that the same is not visible, and access to such device is obtained by boring the apron or trim 70 so that the handle 120 member may be received within the opening of the worm shaft. The shaft *b* may likewise extend either exteriorly or interiorly of the frame member with suitable slots formed in such frame so that the arms and adjusting mechanism may be readily accessible. In the showing of Figure 8, however, the shaft extends exterior the frame the same as in the showing of Figure 1, the said means *f* being 125 the only part concealed. 130

In Figure 9 I have shown a slightly different form of the member *e* and which I designate *g*. In this instance the means *g* includes a part 80 adapted to be secured to the sash and a part 81 at right angles to such part 80, and such part is adapted to pivotally carry a member 82 provided with two spaced flanged rollers 83 and 84. Adapted to be received between such rollers and confined by the flanges thereof, is an arm *h*, which arm in turn is secured to one of the adjusting means *d*. The lever *h* in the showing of Figure 9 is in the form of a rectangular bar and the sides thereof are in close working contact with such rollers 83 and 84. The function of the device as shown in Fig. 9 does not differ from that shown for the device *e*.

It is obvious that various changes and modifications may be made in practicing the invention, in departure from the particular showing, without departing from the true spirit of the invention.

Having thus disclosed our invention, we claim and desire to secure by Letters Patent: 25 In a device of the character disclosed, a shaft, an arm, and means between the shaft and arm for regulating the position of such arm relative to such shaft; said means including a member formed with a recess with- 30 in which the shaft is received, and means receivable in part within said recess for engagement with such shaft; such last named means comprising a screw formed with an annular groove, and such shaft in part being 35 received within such annular groove.

In testimony whereof, we have signed our names to this specification.

CHARLES A. FORWARD.
